UNITED STATES PATENT OFFICE.

GEORGE H. GILBERT, OF GERMANTOWN, PENNSYLVANIA, ASSIGNOR TO
KILBOURN KNITTING MACHINE COMPANY, OF NEW BRUNSWICK, NEW
JERSEY.

KNITTING-MACHINE.

No. 856,860.

Specification of Letters Patent.

Patented June 11, 1907.

Application filed June 24, 1901. Renewed May 18, 1906. Serial No. 317,608.

To all whom it may concern:

Be it known that I, GEORGE H. GILBERT, a citizen of the United States, residing at Germantown, in the county of Philadelphia and State of Pennsylvania, have invented certain new and useful Improvements in Knitting Machines; and I do hereby declare the following to be a full, clear, and exact description of the invention, such as will enable others skilled in the art to which it appertains to make and use the same.

My present invention relates to knitting machines for producing ribbed work and which employ two sets of needles, one set working vertically and the other horizontally, and more particularly to such of said machines as are constructed to produce welts for the tops of half hose and like articles.

In the accompanying drawings, I have illustrated one form in which I have contemplated embodying my said invention and the same is disclosed in the following description and claims.

In the said drawings, Figure 1 is a side elevation of a machine of the class specified in which are embodied my improvements. Fig. 2 is a perspective view of the parts above the bed plate of the machine. Fig. 3 is a view of the parts below the bed plate. Fig. 4 is a top plan view of the said machine. Fig. 5 is a vertical section of the parts shown in Fig. 2. Fig. 6 is a plan view of the needle cylinder nosing. Fig. 7 is an elevation of said nosing. Fig. 8 is a detail of the same. Figs. 9 9' and 10 are views of the cylinder needle cam, and Fig. 11 is a plan view of the tension device for the knitted web. Fig. 12 is a detail showing collar and cam for lifting the tension device, and Fig. 13 is a detail section showing the mode of operating the pawl to give motion to the cams which operate the dial needle and cylinder cam controllers.

In these drawings, A is the supporting standard, which may be of any ordinary or preferred form and A' is the bed plate of the machine. This bed plate is constructed with a circular recess and at the center is provided with an opening through the same. The needle cylinder B is placed in this recess about the central opening. The needle cylinder is provided with the usual needle grooves and with a nosing B' having secured

thereto hook web-holders b as shown in Figs. 6, 7, and 8.

Outside of the needle cylinder is the usual cam cylinder C. This cam cylinder is provided on the underside with the cam e which operates the pattern mechanism and is driven by gearing from the main or driving shaft.

To the underside of the bed plate of the machine is secured the bracket D in which is mounted the gudgeon d. Upon this gudgeon are mounted the cams e' and the ratchet e². A pawl f engages the ratchet with which it is kept in contact by spring f'. The pawl f is pivoted to a rod or bar f² which is normally held in an elevated position by a spring. The upper end of the rod f² engages the cam e and is by this cam depressed once each revolution of the cam cylinder advancing the ratchet one tooth and as the cams e and e' are secured to the ratchet for joint movement these devices are also moved forward with it. The ratchet is a mutilated ratchet having at e² one tooth removed. When the ratchet has been turned to the point at which the pawl falls upon the mutilated portion the ratchet and the cams e, e' come to a state of rest. Upon the gudgeon d is also movably mounted the web friction wheel G having a card cloth surface by means of which web in passing over the same imparts motion to the wheel G.

The web friction wheel G has secured thereto a chain wheel G' upon which is mounted the pattern chain g carrying the pins or projections g' extending toward the ratchet wheel e². The ratchet e² is provided with the pin e² extending toward the chain and chain wheel in the path of the pins g'. The construction is such that when the ratchet is at rest, if motion is given to the friction wheel the chain g will be moved until one of the pins g' comes in contact with the projection e² on the ratchet and moves the said ratchet forward far enough to enable the pawl f to engage the next ratchet tooth when the pawl will again actuate the ratchet and the cams e'.

The cams e, e' control the operation of the dial needles and the length of the stitch made by the cylinder needles. To effect a change in the stitch the cylinder knitting-cam is movably mounted, by being secured to a block o' set in a slot in the wall of the cylinder. This block has a portion extend-

ing above the top of the cam cylinder beneath the end of a lever O which is, at certain periods, automatically operated to depress the cam to lengthen the stitch. A 5 spring o^2 is placed beneath the block and serves to raise it when the pressure of the lever is removed. This lever O is provided with a set screw o^3 which can be raised or depressed to regulate the distance to which 10 the cam is to be moved downward. The opposite end of the lever O is of wedge shape forming cam surfaces on both sides of the lever which are acted upon by the knitting cam controller to move the lever to cause it to depress the cam or permit the spring o^2 to raise it. The lever O is held in its depressed position by a spring detent shown in Fig. 9^a and is held in its raised position by spring o^1 . The cam controller P which is best seen in 15 Fig. 2, is movably fitted in an opening in the bed plate of the machine, and below the bed plate is provided with a spring to maintain it in its lowest position from which it is raised by the cam grade of cam e'. This controller 20 P is provided with shoulders p p' with space enough between them for the cam end of the lever O to pass. When the controller is in its lowest position the wedge or cam end of the lever O in passing between the shoulders 25 p p' will be depressed and the opposite end of the same will be correspondingly raised permitting the cam o to be raised by the spring to the position to knit the main body of the web and when the controller is raised the 30 shoulder p' will act upon the cam end of the lever O to depress the cam o and lengthen the 35 stitch.

The needles of the dial are thrown into and out of action by the cam e through the 40 instrumentality of the needle controller. This controller consists of the rod R movably mounted in the arms q q' of a standard Q. The rod R is also provided with the collars r r' adjustably secured thereto by set screws 45 as shown, each collar having a lug to engage the tappets of a shaft S carried by the dial cam plate, see Fig. 2. The rod R has a part r^x which passes downwardly through the bed plate of the machine into the path of the cam e by which it is raised when desired. This 50 depending part of the rod is in this instance connected with a collar r^z adjustably secured to the rod, by one or more set screws. Between this collar and the arm q of the standard Q is interposed the spring r^z which serves to depress the needle controller when released by the cam e.

The shaft S has tappets s s' and when the rod R is raised the lug or arm of collar r is 55 brought into position to engage the tappet s' and turn the shaft S a partial revolution, when the rod R is in its lowest position the lug or arm of collar r will engage with the tappet s and turn the shaft S a partial revolution in a reverse direction.

The dial cam plate is provided with the usual pivoted switch cam. This cam has a shaft u extending above the upper surface of the dial cam plate and is there provided with a lug u' which is acted upon by the cam s² on the inner end of the shaft S. When it is desired to throw the dial needles into operation the rod R is lowered so that the lug of collar r engages with the tappet s. This causes the shaft S to turn and the cam s² engages the lug u' of the shaft u and turns the shaft u and lug u' into the position shown in Fig. 4, in which position the shaft u and its attached switch cam are secured in position, by the contact of the cam s² with the lug u'. When the needles 80 are to be thrown out of operation the cam s² releases the shaft u and lug u' and permits the butts of the dial needles to close the pivoted or switch cam in a well known way.

The machine is provided with the usual take-up device shown in Figs. 3 and 11, which is operated by a belt from the main or driving shaft of the machine in the usual way. The take-up rollers h h are mounted in a pivoted frame H as usual so that a too rapid movement of the rollers will lift the frame, reduce the friction of the driving belt and stop the movement of the rollers until a sufficient amount of web has been knit to lower the said frame and rollers and restore the friction of the driving belt when the rollers will again be put in motion in a well known way. The web as it descends below the bed plate of the machine passes to the gripping rollers h h of the take-up, passing over and in sufficient contact with the web friction roller G to move the latter as the web is drawn from the machine.

While the welt is being knitted the dial needles are holding their stitches, and it is 105 desirable to remove the tension while they do this to relieve them from strain. I provide a means for doing this which I will now describe.

To the frame H of the take-up is pivoted a rod h' which extends upwardly through the guide d' secured to the bracket D. This rod h' has secured to it an adjustable collar h^x carrying a projection h^z extending toward the cam e. The outer face of the cam e is provided with the outwardly projecting flange e' which extends partly around the cam. This flange is provided with the internal cam surface i and the concentric face i'. The construction is such that when the machine begins the knitting of a welt the cam i will engage the projection h^z on the rod and lift the frame H of the take-up so as to reduce the friction of the driving belt of the take-up and release the web from tension.

To the top of the cam cylinder are secured the standards J J, the upper ends of which are connected by the arched supporting bar J'. To the center of this bar is secured the rod or shaft K and the dial cam plate L is se- 130

secured on the said rod or shaft K. The hub of this cam plate is made fast by set screws and the movement of the dial cam plate in unison with the cam cylinder is secured.

5. The dial needle plate L' having radial needle grooves, is movably mounted on the rod or shaft K and is secured in position by the collar l fixed to said rod or shaft. To the hub of the dial needle plate L' is secured a collar M having two depending arms m m each of which bears against a roller n secured to the underside of the bed plate of the machine in such position that the dial needle plate will be held from any forward movement while the knitted web will be permitted to pass downward between the arms m and the rollers n.

The cam disk e controls the dial plate needles, throwing them into and out of action in a well known way, such needles, as is well understood, being at rest during the making of the welt, while the disk e' controls the knitting cam increasing the length of stitch during the formation of the welt.

25. The operation of the machine is as follows: The web having been placed between the gripping rollers during the knitting of the ribbed body of the fabric, the pawl f rests on the mutilated part of the ratchet e² and the 30 said ratchet and the cams e e' remain stationary. The web passing over the web friction roller G under the strain of the tension device the said roller is moved forward with the chain wheel until one of the pins g 35 comes in contact with the pin e² on the ratchet and moves the ratchet forward until the pawl f engages the teeth of the same. The ratchet is then advanced bringing the cam i under the projection h² on rod k' lifting 40 the rod and releasing the web from tension. This movement of the ratchet and cams throws the dial needles out of action and depresses the knitting cam to lengthen the stitch. The welt is then knit, the pawl acting 45 on the ratchet. When the welt is completed the cams e and e' are brought into position and throw the dial needles again into operation and shorten the stitch to the length desired for ribbed work at the same time the 50 projection h² drops from the concentric face of the flange and the tension is again put upon the web. The ratchet is kept in motion until the pawl f again reaches the mutilated portion when the movement of the 55 ratchet and cams is stopped leaving the cams and other parts in proper position to begin another welt.

When knitting the welt as has been shown, the web is released from tension and to secure 60 the casting off of the stitches and the holding down of the work, I provide the rigid hook web-holders b. The construction is cheaper than the constructions now in use and subserves the useful function set forth.

What I claim and desire to secure by Letters Patent is:

1. In a rib knitting machine, the combination with the dial, its needles and their operating devices, of the needle cylinder, its needles and their operating mechanism, said 70 needle cylinder being provided with rigidly secured hook web-holders, substantially as described.

2. In a rib knitting machine, the combination with the dial, its needles and their operating devices, of the needle cylinder, its needles and their operating mechanism, and a nosing provided with rigidly secured hook 75 web-holders, substantially as described.

3. In a rib knitting machine, the combination with the dial and its needles, operative mechanism for said needles and means for throwing the dial needles out of operation, the cylinder and its needles, means for operating them, said cylinder being provided 80 with rigidly secured hook web-holders, substantially as described.

4. In a rib knitting machine, the combination with the dial and its needles, of the cylinder provided with hook sinkers, its needles, 90 means for operating the dial and cylinder needles, and a web tension device, substantially as described.

5. In a rib knitting machine, the combination with the dial and needle operating mechanism, of the cylinder provided with hooked sinkers, its needle operating mechanism and means for throwing the dial needles out of operation while the cylinder needles continue knitting, substantially as described. 100

6. In a rib knitting machine, the combination with the dial and cylinder, their needles, and operative mechanism, of rigid hook web-holders secured to said cylinder, a tension device for the knitted web, and means for throwing the dial needles out of operation and releasing the web from tension at the same time, 105 substantially as described.

7. In a rib knitting machine, the combination with the needle cylinder and its needles, of a movably mounted knitting cam, a web tension device, and automatic means for moving the cam to lengthen the stitch and to release the web from tension at the same time, substantially as described. 110

8. In a rib knitting machine, the combination with the two series of knitting needles and operating devices, of the hook web-holders and means for throwing the dial needles out of action, substantially as described. 115

9. The combination with the rib knitting mechanism, including a movably mounted knitting cam for the cylinder needles, of a web tension device, means for moving the cylinder knitting cam and to release the web 120 tension, substantially as described.

10. In a rib knitting machine, the combination with the dial and cylinder and needle

operating devices for both dial and cylinder, of rigid web-holders, a tension device for the knitted web, means for throwing the dial knitting mechanism out of operation and means for at the same time releasing the web from tension, substantially as described.

11. In a rib knitting machine, the combination with the dial and cylinder knitting mechanism, rigid web holders, the tension device for the knitted web and the rod and cam for relieving the web from tension, substantially as described.

12. In a rib knitting machine, the combination with the dial and cylinder knitting

mechanism, rigid web holders, the web tension device, means for throwing the dial knitting mechanism out of operation and for releasing the web tension and pattern mechanism controlling the dial knitting mechanism and the tension releasing mechanism, substantially as described.

In testimony whereof I affix my signature, in the presence of two witnesses.

GEO. H. GILBERT.
